COMBINED FLOWER POT HOLDER AND BRACKET THEREFOR

William H. Michaels, 3568 Independence Road,
Cleveland, Ohio 44105

Filed Feb. 27, 1968, Ser. No. 10,743

Term of patent 14 years

(Cl. D35—3)

Fig. 1

Fig. 2

FIG. 1 is a fragmentary front elevational view of a combined flower pot holder and bracket therefor embodying my new design;

FIG. 2 is a side elevational view of the combined flower pot holder and bracket therefor of FIG. 1.

The design is foreshortened for convenience of illustration and the broken lines are for illustrative purposes only.

I claim:

The ornamental design for a combined flower pot holder and bracket therefor, substantially as shown and described.
